Fred J. Harron
Attorney.

UNITED STATES PATENT OFFICE.

MAYER MARGLOUS, OF ST. LOUIS, MISSOURI.

TOE-GLOVE.

1,245,253.

Specification of Letters Patent.

Patented Nov. 6, 1917.

Application filed December 16, 1916. Serial No. 137,301.

To all whom it may concern:

Be it known that I, MAYER MARGLOUS, a citizen of the United States, residing in the city of St. Louis and State of Missouri, have 5 invented a certain new and useful Toe-Glove, of which the following is a specification.

My invention relates to improvements in toe-gloves, and has for its object to provide 10 a device adapted to be positioned upon the foot between the toes thereof to prevent sweating between the toes, thus keeping the toes dry and preventing sore toes, irritations, itching, and even blood-poisoning which 15 often develops after scratching until bleeding sets in.

A further object of the invention is to provide novel means for uniting the several 20 parts of invention, and resiliently but firmly holding the device in position on the foot.

A still further object of the invention is to provide elastic means to permit the device 25 to adjust itself to feet of various sizes.

A still further object of my invention is 30 to obviate the necessity of applying powder, salve, and other toe remedies by the application of my toe-glove.

A still further object of the invention is 35 to provide an article which may be easily applied to the foot between the toes, and due to the flexibility of the toe-pads employed, readily adjust themselves between the toes without interfering with the movements of the toes, such as bandages would do if employed.

With the above and other objects in view, the invention consists of the novel features 40 of construction, arrangement and combination of parts, as more fully hereinafter described, and finally pointed out in the claims hereto appended.

Referring to the accompanying drawings forming a part of this specification wherein like characters of reference denote similar 45 parts throughout the several views:

Figure 1, is a plan view of my improved toe-glove applied to the foot of a person.

Fig. 2, is a perspective view of the article.

Fig. 3, is a side elevation thereof.

50 Fig. 4, is an end view thereof, and

Fig. 5, is a detail, in cross-section, of one of the toe-pads.

In carrying out the aim of my present invention, I employ a plurality of toe-pads, 55 preferably four in number, and each one

preferably a little shorter than the other and as designated 1, 2, 3 and 4.

These toe-pads 1, 2, 3 and 4, are each spaced a suitable distance apart, and are each united, as at 5, 6, 7 and 8, at their lower 60 edges to a non-elastic tape 9. This tape 9 is preferably positioned centrally between the ends of the pads 1, 2, 3 and 4.

The pads 1, 2, 3 and 4 are each suitably united at their upper edges to a pair of 65 elastic bands 10 and 11, as at 12, 13, 14 and 15. These bands 10 and 11 are suitably secured to the pads 1, 2, 3 and 4, near their forward and rearward ends, respectively.

The rear end of each pad has its lower 70 corner curved, as at 16, while the forward end of each pad is curved, as at 17, thus making the top end of each pad longer than the lower edges, as clearly shown in Fig. 2.

It will be observed, that the elastic bands 75 10 and 11, permit the pads to be adjusted to properly fit and adjust themselves between the toes of various sizes of feet, as is manifest. Further, it will be observed, that owing to the non-elastic tape secured to the 80 bottom edge of each pad intermediate the ends thereof, and the elastic bands secured to the upper edge of each pad near each end thereof, that slipping and misplacement of the toe-glove, after once positioned upon the 85 foot, is made impossible.

From Fig. 5 of the drawings it will be observed that each toe-pad is preferably made from a single piece of flexible fabric, 90 preferably very pliable canvas material that is rather soft, and not rough, so as not to scratch the tender flesh between the toes. These pads are each folded at their top edge and suitably stitched, as at 18, along 95 each end and at the bottom.

It will be readily understood that as the pads are each positioned between two toes, any moisture, that may develop between the toes from any cause, will be readily absorbed by the pads thus having the tendency 100 of keeping the toes dry and preventing the various toe and foot ailments due to sweating feet, especially between the toes of the foot.

It will be readily seen from the drawings 105 and the foregoing description, that my toe-glove is not bunglesome when properly positioned between the toes, that it in no way interferes with the putting on of hose and does not take up any particular space so 110

as to make the shoe uncomfortable upon the foot.

From the foregoing description it will be readily seen that I have made a toe-glove for the foot that is very simple in manufacture, composed of very few parts, easily applied or removed to or from the foot, and an article which is highly efficient for the purpose intended.

10. The many advantages of the herein described toe-glove will readily suggest themselves to those skilled in the art to which it appertains.

I am aware that various minor changes 15 may be made in the particular formation and assembly of the several parts, in the material used and in the size of the article; therefore, I do not wish to be limited to the precise construction shown and described, but wish it to be clearly understood 20 that I reserve the right to make any such changes or modifications as may fairly fall within the scope of the appended claims without in any way departing from the 25 spirit of my invention.

What I claim is:

1. A toe glove comprising a plurality of fabric toe spacing pads adapted to be positioned upon the foot between the several 30 toes thereof, a narrow fabric tape for uniting said toe spacing pads at their lower edges, and elastic means for uniting said toe spacing pads at their upper edges at spaced intervals.

2. A toe glove comprising a plurality of 35 fabric toe spacing pads adapted to be positioned upon the foot between the several toes thereof, a narrow fabric tape for uniting said toe pads at their lower edges, and spaced elastic means for uniting said toe 40 spacing pads at predetermined intervals along their upper edges, said toe spacing pads each having their forward and rearward edges suitably beveled.

3. A toe glove comprising a plurality of 45 suitably spaced, flexible fabric toe spacing pads, a narrow non-elastic tape for uniting said toe spacing pads at their lower edges intermediate their ends, and a pair of elastic tapes spaced at intervals along the upper 50 edge of the several toe spacing pads for uniting said toe spacing pads and securely holding the toe glove upon the foot.

4. A toe glove comprising a plurality of 55 longitudinally arranged and vertically disposed flexible, absorbent toe spacing pads arranged in suitable spaced relation, a non-elastic fabric tape fixed to the bottom edge of each toe spacing pad intermediate their ends, and a pair of elastic connecting tapes 60 secured to the upper edge of each toe spacing pad at suitably spaced intervals for holding the toe glove in position upon the foot.

In testimony whereof, I have hereunto 65 signed my name to the specification.

MAYER MARGLOUS.
